UNITED STATES PATENT OFFICE.

WILLIAM FRANKLIN PAYNE, OF STRATFORD, ONTARIO, CANADA.

FURNACE.

1,423,145.

Specification of Letters Patent. Patented July 18, 1922.

Application filed July 30, 1921. Serial No. 488,648.

To all whom it may concern:

Be it known that I, WILLIAM FRANKLIN PAYNE, a subject of the King of Great Britain, residing at the city of Stratford, in the 5 Province of Ontario and Dominion of Canada, have invented certain new and useful Improvements in Furnaces, of which the following is a specification.

This invention relates to improvements in 10 furnaces, and the objects of the invention are to secure an increased efficiency in the distribution of heat, particularly in domestic furnaces and those designed for the heating of houses and buildings, whether hot air or 15 hot water.

More particular objects of the invention are to insure that the maximum amount of 20 heat units in the original combustible material is transferred to the conducting medium, such as the air or water by which it is conducted to the parts of the buildings which 25 are to be heated.

More particular objects of the invention are to insure that the heating current of air 30 or water should be heated to as high a temperature as possible before leaving the furnace and that the products of combustion of the fire in the furnace should remain in contact with the air heating means as long 35 as possible before leaving the furnace.

Further and more general objects of the invention are generally to simplify and improve the construction of the furnace to better adapt it to perform the functions required of it and it consists essentially of the improved construction and arrangement of parts hereinafter described in detail in the accompanying specification and drawings.

Referring to the drawings:—

40 Figure 1 is a longitudinal sectional elevation of an embodiment of the invention.

Figure 2 is a cross section in elevation.

Figure 3 is a sectional plan, showing the air heating pipes.

45 Figure 4 is a front sectional elevation.

Figure 5 is a sectional elevation on the line $x-x$, Figure 4.

Figure 6 is a sectional elevation of an alternative form of the invention as applied 50 to hot water heating systems.

Figure 7 is a sectional plan showing the layout for pipes in the form of the invention used in Figure 6.

55 Figure 8 is a section on the line 8—8, Figure 5.

In the drawings, like characters of refer-

ence indicate corresponding parts in all the figures.

Referring to the drawings; and more particularly to the form of the invention shown 60 in Figures 1 to 5,

A indicates the fire pot of any suitable or convenient design and B the grate therein.

The grate is preferably formed with a plurality of pivoted grate bars 10 having depending lugs 11 which are pivoted to a shaking bar 12 and which may be manually reciprocated by any suitable means, as for instance, by a crank 13 connected to and turning with one of the pivoted grate bars 10 70 whereby when this grate bar is oscillated the shaking bar 12 will cause the remaining grate bars to oscillate, whereby the ashes will drop through the grate into the ash pit C from which they may be drawn through 75 the opening closed by the door D. Fuel may be charged into the fire pot through the opening closed by the door E.

The products of combustion from the fire in the fire pot are adapted at the top of the 80 furnace to be divided by a partition plate 14 which will cause them to pass along channels 15 and 16, the outer side of the channels being formed by air chambers F and G which are thus heated by the products of 85 combustion, these air chambers being provided with bevelled faces 17 at the forward end and with rounded faces 18 at the rear-most end. The products of combustion pass from the channels 15 and 16 to the down 90 flues 19 and 20 which form part of the inner casing H of the furnace. At the bottom of the inner casing, the down flues communicate with forwardly extending passageways 21 and 22 formed by baffle plates 23 and 24 95 which extend from the rear of the casing forwardly beneath the air heating chamber I. Reaching the forward part of the furnace and beneath the air chamber I, the products of combustion then turn and pass 100 through the return flue 25 to the up flue 26 at the back of the casing and from thence to the smoke pipe J which leads to a suitable chimney. During progress of the products of combustion in this way, the heat units 105 therein will be imparted to the air chambers F, G and I. K indicates one of the air heating pipes which rises from a suitable point in the room to be heated. I find it convenient to locate the opening of this pipe about 110 three inches from the floor. It then extends into the air heating chamber I and while in

the chamber passes through a serpentine coil L, finally passing from the serpentine coil L into one of the air chambers F or G. In a similar way, a second air heating pipe M 5 extends from a point adjacent to the floor and connects with a corresponding serpentine coil N located in the air chamber I and from thence discharges into the opposite air heating chamber F or G. These chambers 10 F and G are each provided with a plurality of outlets 27 which when the inner casing is not enclosed by the outer casing will permit the heated air to pass directly into the room to be heated. It is preferable, however, 15 to enclose the inner casing by an outer casing O spaced therefrom and from which pipes P may lead to the rooms or place to be heated. It will be seen that the air drawn into the pipes K and M is heated thoroughly 20 in the heating chamber I by passing through the serpentine coils and is finally further heated in the air chambers F and G.

A hinged damper Q of any convenient form may be provided adjacent to an opening 28 leading from the back of the channels 15 and 16 to the up flue 26. If desired, 25 a certain part of the products of combustion may pass directly to the smoke pipe. This will enable the fire to be started more readily. The damper may be controlled by a rod 29 connected thereto extending through the side of the inner casing and being formed with a crank 30 on the end by which it may be operated, the said crank, if desired, being 30 connected to the operating rod 31 leading to the forward part of the furnace.

For convenience in gaining access to the fire pot, an opening 32 may be provided in the top of the casing inwardly closed by the 40 plate 33. The inner casing itself may be supported from the floor or from any suitable base or legs 34.

The alternative form of the invention shown in Figures 6 and 7 illustrates the invention as applied to water heating systems. In this case, the return pipes of the water heating systems are connected to serpentine coils 40 and 41 within the oven 42 which corresponds to the heating chamber I 45 and is heated by the means described with respect to the form shown in Figures 1 to 5. The outlet conduits 43 and 44 from the coils 40 and 41 pass to further serpentine coils 45 and 46 located in a chamber 47 through 50 which the products of combustion from the fire pot 48 pass. It will be seen that in the form shown in Figures 1 to 5 the cold air will draw into the casing at the bottom from the different rooms and as it passes through 55 the serpentine coils and air heating chambers, is thoroughly heated and will become very hot. The conduits 45 and 46, for convenience in distribution, may be connected by the Y branches 48 and 49 of a header 50 60 which comprises a casing 51 gradually en-

larged from the bottom to the top and having a plurality of distributing pipes 52 extending from the top thereof and the same header may be provided on the return end to combine the pipes from a plurality of rooms 70 into two conduits which lead to the serpentine coils 40 and 41.

In addition to this, there is a certain radiation of heat from the inner casing itself which will either heat the room in which it 75 is placed or will heat the air in the outer casing. It is found by this means possible to effect a considerable economy in the fuel used to heat a building of given size.

As many changes could be made in the above construction and many widely different embodiments of my invention within the scope of the claims, constructed without departing from the spirit or scope thereof, it is intended that all matter contained in 85 the accompanying specification and drawings shall be interpreted as illustrative and not in a limiting sense.

What I claim as my invention is:—

1. In a furnace, a fire pot, a heating chamber, conduits leading the products of combustion across the top, down one end and backwardly and forwardly along the bottom of the heating chamber, and a serpentine heating coil in the heating chamber. 90

2. A furnace comprising a fire pot, a heating chamber, conduits leading the products of combustion from the fire pot across the top, down one end and backwardly and forwardly along the bottom of the heating chamber, a serpentine heating coil in the heating chamber adapted to draw in the air to be heated at one end and discharge the same at the opposite end, a smoke pipe connected to the said conduits being formed at 100 one point with a direct passageway between the conduit extending from the top of the oven and the smoke pipe, and a damper controlling the said opening. 105

3. A furnace comprising a fire pot, a heating chamber, a casing forming conduits at the top end and bottom of the heating chamber through which the products of combustion are designed to pass, baffle plates dividing the conduits at the back and bottom 110 of the heating chamber in such a way that the products of combustion first pass along the top, then downwardly on opposite sides of the ends of the heating chamber, then forwardly beneath the bottom of the heating chamber on the opposite sides thereof then returning separately beneath the centre part of the heating chamber and then upwardly centrally at the back of the heating chamber, and heating coils located within the 115 heating chamber. 120

4. A furnace comprising a heating chamber, a fire pot and top chamber above the heating chamber to which the products of combustion are designed to pass, a baffle 125

plate dividing the chamber longitudinally into two sections, down flues at the end of the heating chamber through which the products of combustion divided by the baffle

5 plates are designed to pass to the bottom of the heating chamber, flues extending forwardly beneath the bottom of the heating chamber through which the products of combustion pass from the down flues forwardly to the front of the heating chamber and a central return flue on the bottom of the heating chamber, an up flue at the back of the heating chamber connected to the return flue, and a smoke pipe connected to the 10 up flue.

5. A furnace comprising a heating chamber, a fire pot, a top chamber above the heating chamber to which the products of combustion are designed to pass, a baffle plate 20 dividing the chamber longitudinally into two sections, down flues at the end of the heating chamber through which the products of combustion divided by the baffle plates are designed to pass to the bottom of the heating 25 chamber, flues extending forwardly beneath the bottom of the heating chamber through which the products of combustion pass from the down flues forwardly to the front of the heating chamber, and a central return flue 30 on the bottom of the heating chamber, an up flue at the back of the heating chamber connected to the return flue, a smoke pipe connected to the up flue and a serpentine heating coil in the heating chamber.

35 6. A furnace comprising a heating chamber, a fire pot, a top chamber above the heating chamber to which the products of combustion are designed to pass, a baffle plate 40 dividing the chamber longitudinally into two sections, down flues at the end of the heating chamber through which the products of combustion divided by the baffle plates are designed to pass to the bottom of the heating chamber, flues extending forwardly beneath 45 the bottom of the heating chamber through which the products of combustion pass from the down flues forwardly to the front of the heating chamber, a central return flue in the bottom of the heating chamber, an up flue 50 at the back of the heating chamber connected to the return flue, a smoke pipe connected to the up flue, and air heating chambers in opposite sides of the top chamber.

7. A furnace comprising a heating chamber, a fire pot, a top chamber above the heating chamber to which the products of combustion are designed to pass, a baffle plate 55 dividing the chamber longitudinally into two sections, down flues at the end of the heating chamber through which the products of combustion divided by the baffle plates are designed to pass to the bottom of the heating chamber, flues extending forwardly beneath 60 the bottom of the heating chamber

through which the products of combustion 65 pass from the down flues forwardly to the front of the heating chamber, an up flue at the back of the heating chamber connected to the return flue, a smoke pipe connected to the up flue, and air heating chambers in 70 opposite sides of the top chamber, said air chambers being formed with bevelled faces at one end and with rounded faces at the opposite end.

8. A furnace comprising a heating chamber, a fire pot, a top chamber above the heating chamber to which the products of combustion are designed to pass, a baffle plate 75 dividing the chamber longitudinally into two sections, down flues at the end of the 80 heating chamber through which the products of combustion divided by the baffle plates are designed to pass to the bottom of the heating chamber, flues extending forwardly beneath the bottom of the heating chamber 85 through which the products of combustion pass from the down flues forwardly to the front of the heating chamber, an up flue at the back of the heating chamber connected to the return flue, a smoke pipe connected to 90 the up flue, air heating chambers in opposite sides of the top chamber, said air chambers being formed with outlets through which the heated air may pass, and a serpentine coil in the outlet discharging into 95 the air chamber having an intake on the exterior of the furnace.

9. A furnace comprising a heating chamber, a fire pot, a top chamber above the heating chamber to which the products of combustion are designed to pass, a baffle plate 100 dividing the chamber longitudinally into two sections, down flues at the end of the heating chamber through which the products of combustion divided by the baffle plates are 105 designed to pass to the bottom of the heating chamber, flues extending forwardly beneath the bottom of the heating chamber through which the products of combustion pass from the down flues forwardly to the 110 front of the heating chamber and a central return flue on the bottom of the heating chamber, an up flue at the back of the heating chamber connected to the return flue, a smoke pipe connected to the up flue, and a 115 plurality of serpentine heating coils having inlets on the outside of the furnace and extending horizontally in the heating chamber and air heating chambers connected to the serpentine heating coils and extending on 120 opposite sides of the top chamber.

In witness whereof I have hereunto set my hand in the presence of two witnesses.

WILLIAM FRANKLIN PAYNE,

Witnesses:

DOROTHY DUTTON,
LEON JOSEPH LONG.
